SMOKING PIPE

Clarence F. Knight, McGrann, Pa., assignor of
one-half to William R. Anderson, Kittanning,
Pa.

Application February 17, 1949, Serial No. 77,000

3 Claims. (Cl. 131—194)

2

This invention relates to smoking pipes and more particularly to smoking pipes having a bypass in which the smoke is cooled and moisture in the smoke is condensed and collected before reaching the smoker's mouth.

It is well known that tobacco smoke as it leaves the bowl of a pipe carries considerable water vapor, vaporized nicotine and other undesirable condensables. In the ordinary pipe these condensable materials collect in the pipe stem and bowl bottom where they form a disagreeable and distasteful liquid which is frequently drawn into the smoker's mouth. Moreover, the smoke from an ordinary pipe has a relatively high temperature, which together with the condensables causes the smoke to bite the tongue and mouth of the user.

I have invented a smoking pipe in which the smoke is cooled and the water vapor and other condensable materials condensed and collected before the smoke reaches the smoker's mouth. This produces a cool, agreeable pleasant smoke which has no tendency to bite the smoker's tongue.

Generally, my invention comprises a bowl and stem member in which the bowl has a hollow, bowl-shaped interior communicating with a longitudinal bore in the stem member. One end of the by-pass means enters the bore at a point adjacent the junction of the bowl and stem member and the other end enters the stem member near the end thereof. A reservoir means having a diameter substantially equal to the bore of the stem member extends into the bore beyond the point where the by-pass means enters the bore near the end of the stem member. Means are also provided on the reservoir for tightly engaging the by-pass means in the stem. A hollow bit means having a shank portion entering the reservoir is provided in the completed structure.

In the accompanying drawings illustrating a present preferred embodiment of my invention;

Figure 1 is a vertical section along the center of a pipe incorporating my invention with a portion of the mouthpiece in elevation.

Figure 2 is a top view in perspective of the pipe of Figure 1.

Figure 3 is a vertical section through the reservoir means of my invention.

Figure 4 is a top plan view of the reservoir means of Figure 3.

Figure 5 is a side view partially in section of a by-pass tube.

Figure 6 is a bottom view of the by-pass tube of Figure 5.

Referring to the drawings I have illustrated a pipe portion 1 in which the bowl portion 2 has a hollow, bowl-shaped interior 3 communicating with a bore 4 in the stem member 5. One end 6 of a by-pass tube 7 enters the bore 4 through an opening 8 in the stem member adjacent the junction of the bowl 2 and stem member 5. The opposite end 9 of the by-pass tube 7 enters the stem member 5 through a slot 10 in the stem member. The end 9 of the by-pass tube projects into the bore 4 and through an opening 11 in the hollow cylindrical reservoir 12 which is rotatably mounted in the bore. The reservoir 12 extends into the bore to a point adjacent the opening 8 in the stem member and is substantially of the same diameter as the interior of the bore 4 so that smoke is prevented from passing by it. A removable screw cap 13 in the end of the reservoir 12 permits the condensate to be removed from the reservoir. A knurled ring 14 on the opposite end of the reservoir permits the reservoir 12 to be rotated within the bore 4. This rotation of the reservoir causes the by-pass tube 7 to be twisted as shown in chain lines in Figure 2, thereby locking it in position in the stem member and reservoir. A hollow bit 15 having a shank 16 is inserted into the reservoir, thereby closing the reservoir. The shoulder 17 of shank 16 forms a dam which prevents the condensates from entering the hollow portion of the bit 15.

When the pipe is being used, smoke generated by burning tobacco in the hollow bowl-shaped interior 3 is drawn back into the bore 4 of the stem member 5 where it is blocked by the cap 13 on the end of the reservoir 12. The smoke then passes through the by-pass tube 7 where it gives up its heat to the atmosphere through the walls of the tube and the condensables such as water vapor are condensed onto the walls. Both the smoke and a large part of the condensate then pass into the reservoir where the condensate is collected and the smoke passes from the reservoir into the hollow bit 15 from whence it goes to the smoker's mouth. When it is desired to empty the reservoir, the reservoir is turned to release the end 9 of the by-pass 7 which is then sprung upwardly to remove the end 9 from the path of the reservoir which is then merely withdrawn from the bore, and emptied through hole 11 or the screw cap 13 may be removed and the contents emptied from the reservoir.

By passing the smoke through the by-pass tube 7, a cool pleasant smoke, free of disagreeable condensables, is delivered to the hollow bit 15. The shoulder 17 on the shank 16 prevents any of the

condensate from running into the bit from which it might be drawn into the smoker's mouth.

It should be noted that all of the parts fit snugly but that the drawings are exaggerated to show a slight spacing between the parts. This exaggerated spacing in the drawings (Fig. 1) is intended for purposes of clarity and not to suggest that a loose fit between the parts be used in constructing a pipe according to this invention.

It is readily apparent that the pipe of my invention produces the cool, pleasant smoke that is so much sought after by pipe smokers. It is also readily apparent that this result is achieved by a simple, inexpensive but highly efficient structure that is easily produced.

Although I have illustrated and described a present preferred embodiment of my invention, it is to be understood that it may be otherwise embodied within the scope of the following claims.

I claim:

1. A smoking pipe comprising a bowl and a stem member having a longitudinal bore therein, said bowl having a hollow, bowl-shaped interior communicating with said longitudinal bore in the stem member, by-pass means one end of which enters the bore adjacent the junction of the bowl and stem member, a transverse slot in the stem member adjacent the end of said stem member through which the opposite end of the by-pass means enters the bore, rotatable reservoir means extending into the bore beyond the point at which said opposite end enters the bore, said reservoir means having an external diameter substantially equal to the diameter of the bore, an opening in said reservoir means to receive said opposite end of the by-pass means, a knurled end on said reservoir means extending above the external periphery of the stem member by means of which the reservoir means may be turned within the bore thereby locking the by-pass means in the stem member, and hollow bit means having a shank portion adapted to enter the reservoir at the knurled end.

2. A smoking pipe comprising a bowl and a stem member having a longitudinal bore therein, said bowl having a hollow, bowl-shaped interior communicating with said longitudinal bore in the stem member, by-pass means one end of which enters the bore adjacent the junction of the bowl and stem member, a transverse slot in the stem member adjacent the end thereof through which the opposite end of the by-pass means enters

the bore, rotatable tubular reservoir means extending into and substantially filling the bore to a point adjacent the bowl and stem member junction end of the by-pass means, a removable cap on said reservoir means, an opening in said reservoir means to receive said opposite end of the by-pass means, a knurled ring on said reservoir means extending above the external periphery of the stem member at the end thereof by means of which the reservoir means may be rotated within the bore thereby locking the by-pass means in the stem member, and hollow bit means having a shank portion adapted to enter the reservoir at the knurled end thereof.

- 15 3. A smoking pipe comprising a bowl and a stem member having a longitudinal bore therein, said bowl having a hollow, bowl-shaped interior communicating adjacent its bottom with said longitudinal bore in the stem member, a thin-walled 20 by-pass tube entering the bore adjacent the junction of the bowl and stem member at an acute angle with the stem member, a transverse slot in the stem member adjacent the end thereof through which the opposite end of the by-pass means enters the bore, rotatable reservoir means 25 extending into and substantially filling the bore to a point adjacent the bowl and stem member junction end of the by-pass tube, an opening in said reservoir means to receive said opposite end of the by-pass tube, a knurled ring on said reservoir means, said ring extending above the periphery of the stem member at the end thereof by means of which the reservoir means may be rotated within the bore thereby deforming the 30 by-pass tube and locking it in the stem member, and hollow bit means having a shank portion entering the reservoir at the knurled end thereof.
